US00D855833S

(12) **United States Design Patent** (10) Patent No.: **US D855,833 S**
 Foley et al. (45) Date of Patent: ** Aug. 6, 2019

(54) **LADDER RAIL**(71) Applicant: **Tricam Industries, Inc.**, Eden Prairie, MN (US)(72) Inventors: **Joseph P. Foley**, St. Paul, MN (US); **Dennis D. Simpson**, Plymouth, MN (US); **Benjamin P. Williams**, Chaska, MN (US)(73) Assignee: **Tricam Industries, Inc.**, Eden Prairie, MN (US)(**) Term: **15 Years**(21) Appl. No.: **29/589,670**(22) Filed: **Jan. 4, 2017**(51) LOC (12) Cl. **25-04**

(52) U.S. Cl.

(57)

CLAIM

The ornamental design for a ladder rail, as shown and described.

DESCRIPTION

FIG. 1 is a perspective view of a ladder rail showing our new design; and,

FIG. 2 is an end elevation view thereof.

The broken lines shown in the figures define the bounds of the claimed design and form no part of the claimed design.

1 Claim, 2 Drawing Sheets# US D855,833 S
